UNITED STATES PATENT OFFICE.

WILLIAM C. J. LANG, OF BUFFALO, NEW YORK, ASSIGNOR OF ONE-HALF
TO WILLIAM G. ELSAESER, OF BUFFALO, NEW YORK.

DESIGN FOR A SEWING-RACK.

No. 38,236.

Specification for Design.

Patented Sept. 11, 1906.

Application filed July 5, 1906. Serial No. 324,863. Term of patent 7 years.

To all whom it may concern:

Be it known that I, WILLIAM C. J. LANG, a citizen of the United States, residing at Buffalo, in the county of Erie and State of New York, have invented a new, original, and ornamental Design for Sewing-Racks, of which the following is a specification, reference being had to the accompanying drawing, forming part thereof.

The figure is a perspective view of the rack, showing my new design.

I claim—

The ornamental design for a sewing-rack, as shown.

WILLIAM C. J. LANG.
